UNITED STATES PATENT OFFICE.

ROBERT ALBERT WALTER, OF NEW YORK, N. Y.

DESIGN FOR A DRUGGIST'S SIGN.

No. 39,568.

Specification for Design.

Patented Sept. 22, 1908.

Application filed August 20, 1907. Serial No. 389,415. Term of patent 3½ years.

To all whom it may concern:

Be it known that I, ROBERT ALBERT WALTER, a citizen of the United States, residing at 939 Washington avenue, New York city, in the county of New York and State of New York, have invented a new, original, and ornamental Design for Druggist-Signs, of which the following is a specification, reference being had to the accompanying drawing, forming part thereof.

The figure is a perspective view of a druggist's sign showing my design.

I claim.

The ornamental design for a druggist's sign as shown.

ROBERT ALBERT WALTER.
